(57) **CLAIM**

The ornamental design for a positioning device for a surgical instrument as shown and described.

DESCRIPTION

FIG. 1 is a front, right-side, and top perspective view of a positioning device for a surgical instrument showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, right-side, and bottom perspective view thereof;

FIG. 9 is a perspective view of the positioning device for a surgical instrument of FIG. 1 shown in an environment; and, FIG. 10 is a perspective view of the positioning device for a surgical instrument of FIG. 1 shown in another environment.

The evenly dashed broken lines depict portions of the positioning device for a surgical instrument that form no part of the claimed design.

The dot-dashed broken lines in FIGS. 9 and 10 are for illustrating environment structure only and form no part of the claimed design.
